(57) **CLAIM**

The ornamental design for a reflective casing, as shown and described.

DESCRIPTION

FIG. 1 is a front, top, right perspective view of a reflective casing, showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, top, left perspective view thereof.

The claimed design is indicated by the relatively dark portions in the drawings. The relatively light portions, enclosed by the broken lines shown in drawings, are included for the purpose of illustrating portions of the reflective casing, and form no part of the claimed design.
